The ornamental design for a magnetic disc storage unit for a computer as shown and described.

DESCRIPTION

FIG. 1 is a front, top and right side perspective view of a magnetic disc storage unit for a computer according to the design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a cross-sectional view taken along line 8-8 of FIG. 2;

FIG. 9 is a cross-sectional view taken along line 9-9 of FIG. 2;

FIG. 10 is an enlarged view of the portion shown in BOX 10 of FIG. 1, included for clarity of illustration;

FIG. 11 is an enlarged view of the portion shown in the dot-dash line box labeled 11 in FIG. 1;

FIG. 12 is an enlarged view of the portion shown in the dot-dash line box labeled 12 in FIG. 2;

FIG. 13 is an enlarged view of the portion shown in the dot-dash line box labeled 13 in FIG. 8;

FIG. 14 is an enlarged view of the portion shown in the dot-dash line box labeled 14 in FIG. 1;

FIG. 15 is an enlarged front elevational view thereof;

FIG. 16 is an enlarged view of the portion shown in the dot-dash line box labeled 16 in FIG. 6;

FIG. 17 is an enlarged view of the portion shown in the dot-dash line box labeled 17 in FIG. 7;

FIG. 18 is an enlarged view of the portion shown in the dot-dash line box labeled 18 in FIG. 8; and,

(Continued)

FIG. 19 is an enlarged view of the portion shown in the dot-dash line box labeled 19 in FIG. 9.

The broken lines in the drawings show portions of the magnetic disc storage unit for a computer that form no part of the claimed design. The dot-dash line boxes shown in FIGS. 1-2 and 6-9 define the enlarged portions shown in FIGS. 10-14 and 16-19 and form no part of the claimed design.
